UNITED STATES PATENT OFFICE.

CHARLES F. WAGNER, OF ATLANTIC CITY, NEW JERSEY.

SUPPORT FOR FURNACE ARCHES.

Application filed July 8, 1921. Serial No. 483,333.

To all whom it may concern:

Be it known that I, CHARLES F. WAGNER, a citizen of the United States, residing at Atlantic City, in the county of Atlantic and 5 State of New Jersey, have invented new and useful Supports for Furnace Arches, of which the following is a specification.

This invention relates to means for supporting furnace arches of the "suspended" 10 type.

It is an object of the present invention to provide hollow supporting beams which are water cooled, all of the beams supporting the arch being connected so that a constant circulation of water can be set up and 15 the burning of the beams prevented.

Another object is to provide water cooled beams which can be substituted readily for the solid beams heretofore employed, the 20 water used for cooling these beams being carried off in a heated condition so that it can be used for various purposes, such as preheating the feed water, etc.

With the foregoing and other objects in 25 view which will appear as the description proceeds, the invention resides in the combination and arrangement of parts and in the details of construction hereinafter described and claimed, it being understood 30 that, within the scope of what is claimed, changes in the precise embodiment of the invention shown can be made without departing from the spirit of the invention.

In the accompanying drawings the preferred form of the invention has been shown.

In said drawings—

Figure 1 is a longitudinal section through a portion of a furnace showing an arch supported by a beam such as constitutes the 40 present invention.

Figure 2 is an enlarged section on line 2—2, Figure 1.

Figure 3 is an elevation of one of the hangers, adjacent parts being shown.

Fig. 4 is a section on line 4—4, Fig. 1.

Referring to the figures by characters of reference 1 designates hollow beams having longitudinal depressions 2 in the sides thereof adjacent the lower faces of the beams 50 so that when the furnace brick or tile T are to be supported they can be slid along the bottom portions of these beams, there being

inwardly extending portions T' on the tile or brick for extending into the depressions 2 and thus holding the beams and tile interlocked. Tile have heretofore been mounted in the same manner upon solid beams and in practice the hollow beams can be made or proportioned so as to be engaged by tile of standard sizes although specially constructed tile can be used or, if necessary, the inwardly extending portions T' of standard tile can be partly broken away to receive the reduced portions of the beams between them.

The beams are connected by pipes 3 leading from any suitable source of water supply and to any desired point of use so that a constant circulation of water can be set up within and between the beams with 70 the result that they will be kept cool. The upper ends of the beams can be shaped like the ordinary supporting beams and are held in place by means of hangers 4 adjustably mounted in plates 5 arranged between and 75 bearing on girders or beams 6 forming part of the furnace structure. If desired one of the pipes 3 can constitute part of the supporting means, this pipe being engaged by the hangers as shown in Figure 3.

A hollow bracket support 7 can be supported beyond and below the lower end of each beam 1, these castings being connected by pipes 8 so that a circulation of water can be set up through the castings. These 85 bracket supports, like the beams 1, have grooves 9 in the sides thereof adjacent their inner or active edges so that the tile or brick T can be threaded onto said edge portions of the bracket supports.

By supporting the tile from water cooled members the objectionable features heretofore present in furnaces of the "suspended arch" type are eliminated and the danger of the arch caving in or becoming unduly warped is practically eliminated.

What is claimed is—

In a furnace structure a hollow bracket support having grooves in opposed faces thereof, hollow beams separate from but supported adjacent the bracket support, said beams having grooves in the opposite faces thereof, pipes connecting the bracket supports, pipes connecting the beams, tiles pro-

jecting into the grooves in the bracket supports and beams and held assembled by engagement therewith, and end supports connected to a pipe of each beam for supporting those ends of the hollow beams remote from the bracket supports.

In testimony that I claim the foregoing

as my own, I have hereto affixed my signature in the presence of two witnesses.

CHARLES F. WAGNER.

Witnesses:

RALPH E. BRODE,
JENNIE CABEN.
